UNITED STATES PATENT OFFICE.

HERMAN L. WAGNER, OF MOUNT VERNON, NEW YORK, ASSIGNOR TO UNDERWOOD
TYPEWRITER COMPANY, OF NEW YORK, N. Y., A CORPORATION OF NEW JERSEY.

TYPE-WRITING MACHINE.

No. 904,737.

Specification of Letters Patent. Patented Nov. 24, 1908.

Application filed March 9, 1907, Serial No. 361,521. Renewed October 17, 1908. Serial No. 458,302.

To all whom it may concern:

Be it known that I, HERMAN L. WAGNER, a citizen of the United States, residing in Mount Vernon, in the county of Westchester and State of New York, have invented certain new and useful Improvements in Type-Writing Machines, of which the following is a specification.

This invention relates principally to that 10 class of tabulating mechanism for typewriting and other machines in which independently operable denomination keys are provided, although certain features thereof may be applied to other tabulating mechanisms.

15 This invention is in the nature of an improvement on the construction shown in my application No. 337,076, in which denomination keys are mounted in a row on the ends of short arms which extend forwardly from 20 the front bar of the paper carriage, denomination stops being rigidly connected to said arms and depressible independently one of another by the keys to engage column stops provided upon the framework; said denomination 25 stops placed side by side at letter space intervals, and each key arm with its stop arm forming a bail, the bails being of graduated sizes and nested together in two sets, and key-bearing arms diverging or fan- 30 ning out at each side of the sets of stops to compensate for the greater length of the row of keys.

According to the present invention, four 35 single-arm stops are employed at the middle of the system, said stops having diverging forward extensions to carry their keys, means being provided for compensating for the great extent to which the outer keys of the four are offset from their stop-arms. 40 The remaining six stop-arms in the system are devoid of keys, but four of them are each rigidly connected by an overlying cross-bar to a companion arm, the latter having a divergent key-bearing forward extension.

45 The remaining two stop-arms are connected by rear cross-bars to companion arms bearing the key extensions; or in other words, these two remaining devices are in the form of bails, one arm of each bail bearing a key, 50 and the other arm forming a denomination stop, and the latter is placed between the other stops in the system.

Figure 1 is a plan of the front upper portion of an "Underwood" typewriting machine provided with the improvements.

Fig. 2 is a front elevation of the parts seen at Fig. 1. Fig. 3 is an enlarged plan showing details of the four denomination stops at the middle of the system. Fig. 4 is a sectional plan of the parts seen at Fig. 3. Fig. 5 is a sectional side elevation of the parts seen at Fig. 1, taken on the line X—X. Fig. 6 is a sectional view illustrating a column stop, and a bar on which it is revolubly mounted. Fig. 7 is a plan of the cover-plate and keys. Fig. 8 is a rear perspective view of the supports of the denomination keys, and showing also in dotted lines the de- 60 pressible cover plate. Fig. 9 is a sectional rear elevation illustrating the operation of a latch to hold the cover-plate against depression. 65

The usual cylindrical platen is illustrated at 1, and is mounted upon a shifting platen frame, (not shown), the latter mounted in the usual manner upon a carriage comprising side bars 2 and front bar 4. The carriage is propelled by the usual spring barrel 5 and strap 6, and is provided with a letter spacing rack 7 to mesh with a pinion 8, the latter forming part of the usual escapement or letter-feeding mechanism. Said rack is usually provided at its end with a pair of arms 9 hinged at 10 upon the carriage frame and provided with a forwardly extending de- 70 pressible arm 11, so that by depressing the arm, the rack may be raised clear of the pinion 8, and the carriage may run along freely under the influence of the propelling spring 85 5. The carriage has a front roll 13 running upon a track 14.

Extending along the carriage in front of the platen is a horizontal rock shaft 15 mounted in ears 16 projecting from a bracket 17, the latter secured in any suitable manner upon the top of the front carriage bar 4. Said rock shaft extends through the end bar 2 of the carriage and is provided with a short arm 19, to vibrate a lever 20, and thereby de- 90 press the arm 11 of the rock frame 7, 9, and release the carriage. By means of ears 22 and screws 22^a a forwardly extending plate 23 is fixed upon said shaft, so that by de- 95 pressing said plate, the carriage may be released. This plate is of a size to cover the denomination-stop mechanism, to protect the same from dust. These denomination keys 100 24, ten of which are shown, operate a set of denomination stops 25, the latter formed upon the forward ends of arms 26 and lo- 105 110

cated at letter space intervals. Each key is rigidly connected to its stop-arm, but the manner of connection is varied, as will now be explained.

The four middle stop-arms 26 in the system are hinged at their rear ends upon the rod 15, and extensions 27 branch from said stop arms 26, above the stops 25, and diverge forwardly, the denomination keys being fixed directly upon their forward ends. Said diverging extensions 27 branch from the arms 26 at points between the ends of the latter. Thus each stop is in the form of a single-arm bearing a key. The outer keys of this middle group of four, it will be seen, at Fig. 1, diverge considerably from their stop-arms 26, and in order to compensate for this cranking to avoid undue binding and consequent difficulty of operation, each of said outer arms is provided with a hub 28 of considerable length, whereby it is mounted upon the shaft 15, so that the arm has a long bearing on said shaft. These hubs may touch each other as seen at Fig. 4, and at their contiguous ends may be reduced, as at 29 to receive the narrow hubs 30 of the two middle stop-arms 26, said hubs 30 turning freely upon the bearings 29 and independently of the latter, so that another stop may be depressed without stirring any of the others. All of the stop-arms are guided at their forward ends in a comb 31, which is in the form of a vertical flange produced by bending up the front part of the plate 17; slots 32 being cut in said flange 31 to receive said stop-arms, and the stops 25 projecting forwardly from said comb in position for pressing into line with one or more column stops 33. Upon the flanks of the middle group of four column stop-arms 26, are two groups of three stop-arms 26^a each, the forward ends of these stop-arms being devoid of keys.

The outermost stop-arm is in each instance connected by a cross-bar 34 to an arm 35 having a key-bearing extension 36, said arms 35 and 26^a being rigidly connected by the bar 34 and preferably formed in one piece therewith. The next inner stop arm 26^a, in each instance, forms one arm of a bail, the other arm being designated as 37 and being joined thereto by a cross-bar 38 at the rear ends of said arms. The arm 37 carries a key-bearing extension 39. The next inner stop arm 26^a, in each instance is united by a cross-bar 40 to an arm 41, carrying a key-bearing extension 42. The cross-bars 40 and 37 directly overlie certain of the described arms, as seen clearly at Fig. 1, and are placed one back of the other to give clearance. By this arrangement, the keys and stops are given the same regular order, as illustrated, while the outer three keys at each end of the system are given broad pivotal bearings on the shaft 15 and consequent ease of action; all of the arms 26^a, 41, 37

and 35 being hinged directly upon said shaft. It will be seen that the grouping of the stops and connections is exceedingly compact in every way, which is a desideratum in typewriter carriages, especially where the mechanism is placed upon the front of the carriage, and the types strike upon the front of the platen, as seen at Fig. 5, because the operator's view of the writing is not obstructed, and the parts, owing to their compactness, may be made very light, thus avoiding the objection of unduly weighting the paper carriage, the lightness of which must be preserved in order to conduce to speed of writing. In some cases, the outermost key and stop, at each end of the system, may be omitted. The bracket 17 is formed at its rear portion with an upturned comb 43, to guide certain of the arms.

In operation, any desired denomination key is depressed, the finger at the same time pressing down the cover-plate 23 which is open immediately in rear of its front edge portion to receive the denomination keys, each key preferably having a separate opening 44 in the plate. The carriage is then drawn along by the spring 5 until arrested by the engagement of the depressed stop with a column stop 33 provided upon the framework. The key and cover-plate are then relieved of pressure and the type keys manipulated in the usual manner, types 45 striking as usual on the front of the platen 1. The depressible cover-plate 23 may be used for releasing the carriage for ordinary purposes, as well as during the operation of tabulating as it forms a very convenient release key. The stops 33 are adjustable along a rack 33^a mounted upon the framework, as set forth in my pending application No. 315,609. Each column stop has a ball 46 pressed by a spring 47 into either of two grooves 48 and 49 formed in a rod 50 to hold the stop either in working position, as shown at Fig. 5, or in an upright position to permit an index 51 formed upon the stop, to coöperate with the usual scale 52 provided upon the framework of the machine for use with the ordinary carriage index (not shown).

It will be seen that the keys are not only mounted at the front of the machine where they may be conveniently seen and operated, but also that they are below the line of vision. That is, the tabulating mechanism does not come between the line of writing on the platen and the eyes of the operator. Each of the key-bearing arms is provided on its under edge with a leaf spring 53 fixed at its rear end in said arm, and bearing at its free forward end is a notch 54 Fig. 8, formed in the lower ends of the guiding slots 32, to restore the keys to normal positions after actuation. The cover plate is restored by a spring 55, Fig. 1.

A latch 56, Fig. 8, projects from one end of a bar 57, which has horizontal slots 58 to slide upon screws 59, whereby said latch may be slid under the edge of the plate 23, to support the same against depression. At the opposite end of the bar is formed another latch 60, which normally underlies an opening 61 in the plate 23, but by a movement of the bar 57 to the Fig. 8 position, it is brought beneath the body of the plate to prevent this side of the latter from being accidentally depressed. A hook 62 above the latch 56 may also be provided to limit the upward movement of the plate 23 caused by the spring 25. A portion of the bar 57 may be bent rearwardly to form a flange 63, to overlie the compressible arms and form a stop for the upward movements of the latter.

Having thus described my invention, I claim:

1. A tabulating mechanism including a system of stop-arms hinged upon a common axis, and keys for said stop-arms; said arms comprising a middle group of four single arms bearing divergent forward extensions provided with keys, and the remaining stop-arms being devoid of keys, but being connected by cross-bars with key-bearing arms.
2. A tabulating mechanism including a system of stop-arms hinged upon a common axis, and keys for said stop-arms; said arms comprising a middle group of four single arms bearing divergent forward extensions provided with keys, and the remaining stop-arms being devoid of keys, but being each connected by cross-bars with key-bearing arms, each cross-bar overlying certain of the arms.
3. A tabulating mechanism including a system of stop-arms hinged upon a common axis, and keys for said stop-arms; said

arms comprising a middle group of four single arms bearing divergent forward extensions provided with keys, and the remaining stop-arms being devoid of keys, but being each connected by a cross-bar with a key-bearing arm, each cross-bar overlying certain of the arms, and said cross-bars occupying positions one forward of another at each side of the system. 45

4. A tabulating mechanism including a system of stop-arms hinged upon a common axis, and keys for said stop-arms; said arms comprising a middle group of four single arms bearing divergent forward extensions provided with keys, a stop-arm at each side of said group being unprovided with a key and being connected by a cross-bar with a key-bearing arm, and a stop-arm 60 at the outer side of each of the last-mentioned stop-arms being in the form of one arm of a bail whose cross-arm is in rear of certain of the described arms, and whose outer arm carries a key; the first-mentioned 65 cross-arm overlying the last-mentioned stop-arm.

5. A tabulating mechanism including a system of stop-arms hinged upon a common axis, and keys for said stop-arms; said 70 arms comprising a middle group of four single arms bearing divergent forward extensions provided with keys, and the remaining stop-arms being devoid of keys, but being each connected by a cross-bar with a key-bearing arm, the outer stop-arms of said group of four being provided with hubs, where by they are hinged upon said shaft, and the inner arms of said group being hinged loosely upon said hubs. 75
